FIG. 2

FIG. 3

FIG. 1

FIG. 4 5

FIG. 5

FIG. 6

FIGURE 1 is a view in side elevation of a dip basket for chemically treating objects showing my new design, the opposite side being a mirror image of said side shown;

FIGURE 2 is a view in top plan thereof;

FIGURE 3 is a view in bottom plan thereof;

FIGURE 4 is a view in end elevation thereof, the opposite end being a mirror image of said end shown;

FIGURE 5 is a view in section as seen from the line 5-5 of FIGURE 4; and

FIGURE 6 is a view in section as seen from the line 6-6 of FIGURE 2.

The dominant features of my invention reside in the portion shown in full line, the handle being fragmentarily shown in FIGURES 1, 3 and 4 for convenience of illustration.

I claim:

The ornamental design for a dip basket for chemically treating objects, as shown and described.
